INVENTOR

Charles Miller

BY

N. J. Criswell,
ATTORNEY

UNITED STATES PATENT OFFICE.

CHARLES MILLER, OF LONG ISLAND CITY, NEW YORK.

CLASP ATTACHMENT FOR BUCKLES.

Application filed February 3, 1926. Serial No. 85,740.

This invention relates more particularly to a class of fastening devices.

My invention has for its object primarily to provide a clasp attachment designed to be employed on buckles especially those of ornamental types for enabling the buckles to be mounted on appropriate supports such as women's slippers, pumps and the like, and which is of a form whereby the buckles may be removed for permitting the front pieces of buckles of different designs to be interchangeably used on the footwear or for allowing the buckles to be removed so that overshoes may be worn on the footwear as occasion requires.

The invention contemplates the provision of two spaced rods having one of their ends integrally formed in the fashion of a substantially U-shaped clip, and the free ends 20 of the rods or leg members of the clip are hinged to the rear face of the front piece or body of the buckle which may be of a plain or fanciful design of the class preferably used on the fronts of the vamps of pumps and slippers for women. The rods or leg members of the clip may be crimped to provide teeth, and on the leg members of the clip is a removable support for being mounted on the footwear. The support has 25 a tubular member through which the rods or legs of the clip are slidably disposed. On the wall of the tubular member may be provided teeth for engaging the teeth of the clip to prevent the front piece 30 from accidentally moving thereon, and means is provided for detachably fastening the other ends of the rods or looped end of the clip to the front piece so that the buckle will be removably held on the footwear for 35 interchangeable use when desired.

A further object of the invention is to provide a clasp attachment for buckles of a simple, efficient and durable construction which may be made in appropriate sizes and 40 shapes.

With these and other objects in view, the invention will be hereinafter more fully described with reference to the accompanying drawing forming a part of this specification in which similar characters of reference indicate corresponding parts in all the views, and will then be pointed out in the claims 50 at the end of the description.

In the drawing Figure 1 is a rear elevation of the front piece of a buckle with one

form of my improved clasp attachment applied thereto.

Fig. 2 is an enlarged sectional view, partly in detail, taken on the line 2-2 of Fig. 1, and

Fig. 3 is an enlarged sectional view taken on the line 3-3 of Fig. 1.

The device or clasp attachment has a clip 10 which may be a form including two spaced spring rods 11, 12 or the clip may be substantially U-shaped, as shown, so that the rods 11, 12 serve as the legs of the clip, and the joined end portions of the legs of the clip provide a spring loop, as 13. The free ends of the legs 11, 12 of the U-shaped 70 clip are bent inwardly toward each other. These bent ends are rotatively disposed in the ends of an eye, as 14, which extend from the central part of the upper end of a front piece 15 of a buckle 16 for hinging 75 the clip to the front piece, and the bent end portions of the legs of the clip under the eye 14 are strapped together, as at 16a. The front piece 15 or ornamental part proper of the buckle may be of a plain or fanciful 80 design, such as used on the fronts of the vamps of slippers, pumps and like footwear worn by women. The clip 10 is preferably of a length so that its looped end 13 terminates in proximity to the lower edge of the 85 front piece 15. The clip may be swung on its hinge toward and from the rear face of the front piece of the buckle, and the central portions of both of the legs 11, 12 of the clip may be respectively crimped to provide teeth, as 17, 18, the teeth of each leg being aligned with the teeth of the other leg.

Slidably adjustable on the yielding legs 11, 12 of the clip 10 is a support 19 for detachably mounting the front piece 15 on footwear. The support 19 is preferably in the form of a substantially rectangular plate 20, and protruding from the central part of one face of this plate is an approximately U-shaped strap 21 which provides a 100 tubular member having a passage 22 extending lengthwise of the plate toward its ends. The strap member 21 may be integrally formed with the plate by slitting the central parts of the crosswise in proximity to its 105 ends, and the part of the plate embraced between the slits is struck outwardly in the fashion of a U. The passage 22 is thereby of somewhat a rectangular shape and is provided on one face of the plate 20. The 110

legs of the clip are disposed through the passage with the end walls of the passage in movable contact with the legs for mounting the support on the clip. The rectangular passage is of a width for yieldingly holding the legs of the clip in determined spaced relation, and when the legs of the clip are of forms having the teeth 17, 18, on the end walls of the rectangular passage 22 of the plate 20 of the support 19 are provided two teeth, as 23, 24, which protrude inwardly of the passage, and these teeth are in releasable engagement with the crimps or teeth 17, 18 of the legs of the clip. The plate 20 of the support 19 is somewhat less than the lengths of the portions of the legs 11, 12 of the clip 10 between the loop 13 and strap 16^a of the legs so that the front piece of the buckle with the clip may be slidably adjusted upwardly and downwardly relative to the support. There may be a sufficient number of pairs of the teeth 17, 18 on the legs of the clip for allowing a number of adjustments of the front piece and clip to be made with respect to the support 19 for permitting the buckle to be suitably positioned on the footwear, as will be later explained.

In the plate 20 of the support 19 at the lower end of the passage 22 are a number of spaced holes 25, and in the plate at the upper end of the passage are also a number of holes 26 for allowing the support to be stitched to the vamp of a slipper. Serving as means to permit the second end of the clip 10 to be detachably fastened to the front piece 15 of the buckle on the central part of the lower end of the front piece is a pin, as 27, having its shank of a length so that its head 28 is spaced from the front piece. The head 28 of the pin is partly spherical in shape, and the head is of a size somewhat larger than the width of the loop 13 of the U-shaped clip 10. The pin 27 is also positioned for being received in the loop of the clip. When the device is applied to a slipper or pump the support 19 is secured on the vamp of the footwear by stitching the plate 20 through the holes 25, 26 to the vamp after removal of the support from the front piece 15 by removing the loop from the pin 27 and then slidably moving the clip 10 out of the passage 22 of the plate 20 of the support. The front piece of the buckle is subsequently remounted on the support 19 by the clip being inserted through the passage 22 of the support, and the looped end of the clip is sprung over the head 28 of the pin 27 of the front piece for mounting the buckle on the support. By then suitably adjusting the front piece and clip on the support the front piece will be releasably held against accidental movement by the teeth 23, 24 of the support engaging the proper pair of the teeth 17, 18 of the legs of the clip. When

desired the buckle may be interchangeably used with buckles of other forms which are also provided with the clasp attachment.

In the foregoing description, I have embodied the preferred form of my invention, but I do not wish to be understood as limiting myself thereto, as I am aware that modifications may be made therein without departing from the principle or sacrificing any of the advantages of this invention, therefore, I reserve to myself the right to make such changes as fairly fall within the scope thereof.

Having thus described my invention, I claim as new and desire to secure by Letters Patent:—

1. A clasp attachment for buckles having a front piece, comprising two spaced crimped rods having one of their ends hinged to the rear face of the front piece, a support having a tubular member slidably adjustable on the rods and the tubular member having teeth releasably engaging a number of the crimps of the rods, and means for detachably fastening the other end of the rods to said front piece.

2. A clasp attachment for buckles having a front piece, comprising a substantially U-shaped clip having the free ends of its leg members hinged to the rear face of the front piece, a separate support having a tubular member through which the legs of the clip are disposed, and means on the rear face of the front piece for being engaged by the looped end of the clip to detachably clamp the clip and front piece together.

3. A clasp attachment for buckles having a front piece, comprising a substantially U-shaped clip having toothed leg members and the free ends of its leg members hinged to the rear face of the front piece, a support having a tubular member slidably adjustable on the legs of the clip and the tubular member having teeth releasably engaging a number of the teeth of the legs of the clip, and means on the rear face of the front piece for being engaged by the looped end of the clip to detachably clamp the clip and front piece together.

4. A clasp attachment for buckles having a front piece, comprising a substantially U-shaped yielding clip having the free ends of its leg members hinged to the rear face of the front piece, a supporting plate having on one of its faces means providing a passage through which the legs of the clip are disposed, and a pin with a head projecting from the rear face of the front piece for being received in the looped end of the clip to detachably clamp the clip and front piece together.

5. A clasp attachment for buckles having a front piece, comprising a substantially U-shaped clip having toothed leg members and the free ends of the leg members hinged

to the rear face of the front piece, a supporting plate having on one of its faces means providing a passage through which the legs of the clips are disposed and the 5 wall of the passage having teeth releasably engaging a number of the teeth of the legs of the clip, and a pin with a head projecting from the rear face of the front piece for being received in the looped end of the 10 clip to detachably clamp the clip and front piece together.

6. A clasp attachment for buckles, in combination with a front piece having

hinged to its rear face one of the ends of two spaced toothed rods, a supporting plate 15 having on one of its faces a strap member providing a passage through which the rods are removably disposed and the wall of the passage having teeth in removable engagement with the teeth of the rods, and means 20 for detachably clamping the other ends of the rods and front piece together.

This specification signed this 2nd day of February, A. D. 1926.

CHARLES MILLER.
